FIG.16

FIG. 1 is a plan view of a chain guard incorporating my new design.

FIG. 2 is an end view of the keeper portion as seen from the left in FIG. 1.

FIG. 3 is an end view of the keeper portion as seen from the right in FIG. 1.

FIG. 4 is a bottom view of the keeper portion as seen from the bottom of FIG. 1.

FIG. 5 is a rear view of the keeper portion.

FIG. 6 is a sectional view taken along the line 6-6 in FIG. 1.

FIG. 7 is an enlarged fragmentary sectional view taken along the line 7-7 in FIG. 1.

FIG. 8 is an enlarged fragmentary sectional view taken along the line 8-8 in FIG. 1.

FIG. 9 is an enlarged fragmentary sectional view taken along the line 9-9 in FIG. 1.

FIG. 10 is an enlarged fragmentary sectional view taken along the line 10-10 in FIG. 1.

FIG. 11 is a top view of the base portion as seen from the top of FIG. 1, with the sections being the same as shown in FIGS. 7 and 9.

FIG. 12 is a bottom view of the base portion as seen from the bottom of FIG. 1.

FIG. 13 is a side view of the base portion as seen from the right in FIG. 1.

FIG. 14 is a rear view of the base portion.

FIG. 15 is an enlarged sectional view taken along the line 15-15 in FIG. 1.

FIG. 16 is an enlarged sectional view taken along the line 16-16 in FIG. 1.

The portions shown in broken lines are for purposes of illustration only.

This application is a division of my co-pending application Ser. No. 149,121, filed June 1, 1971.

I claim:

The ornamental design for a chain guard, as shown and described.
